DIAGNOSTIC CLINICAL INSTRUMENT HAVING SUPPORTING MEANS

Bernard McDonald, Malibu, Calif., assignor to Medical
Testing Systems, Inc., Beverly Hills, Calif.

Filed Mar. 11, 1971, Ser. No. 123,489

Term of patent 14 years

Int. Cl. D24—03

U.S. Cl. D83—12

FIG. 1 is a perspective view of a diagnostic clinical instrument having supporting means showing my new design;

FIG. 2 is a front elevational view thereof;

FIG. 3 is a left side elevational view thereof;

FIG. 4 is a rear plan view thereof;

FIG. 5 is a top plan view thereof; and

FIG. 6 is a bottom plan view thereof.

The right side elevational view is substantially the same as the opposite side that is shown.

I claim:

The ornamental design for a diagnostic clinical instrument having supporting means, substantially as shown and described.
